RELEASABLE STARTER JAW HOLDING
MEANSCharles S. Metsger, Lodi, N. J., assignor to Ben-
dix Aviation Corporation, Teterboro, N. J., a
corporation of Delaware

Application November 12, 1946, Serial No. 709,272

6 Claims. (Cl. 192—42)

1

The invention hereof relates to means for holding a starter jaw or the like against rotation whereby it is moved axially into engagement with an engine element, and for releasing the jaw from such holding for rotation to start the engine.

In a direct cranking starter of a usual type, the starter jaw is frictionally held against rotation while it is being moved axially to engage an engine jaw element or the like, whereupon it is rotated to start the engine while still being frictionally held as aforesaid.

Such prior structure imposes the friction load or drag on the starter jaw during rotation of the latter, which causes loss of operating efficiency and is otherwise disadvantageous.

Among the objects of the present invention are to overcome the above-mentioned disadvantages and to do so by novel effective means.

Another object is to automatically release the holding effect of the holding means on a starter jaw at, or about, the time it engages the engine jaw and rotates to start the engine, which means automatically resumes its holding effect upon retraction of the jaw.

Another object is to provide a device of the above-indicated character which is simple and durable in construction, economical to manufacture, and effective in its operation.

These and other objects and features of the invention are pointed out in the following description in terms of the embodiment thereof which is shown in the accompanying drawing. It is to be understood, however, that the drawing is for the purpose of illustration only, and is not designed as a definition of the limits of the invention, reference being had to the appended claims for this purpose.

In the drawing:

Figure 1 is a side view, partially in section and partially in elevation, of a portion of a direct cranking starter structure, embodying the invention in one form; and

Figure 2 is a view, similar to a portion of Figure 1, showing the invention in modified form.

In Figure 1, which shows only so much of the starter sufficient for an understanding of the invention, the device comprises a rotor or member 10 having jaws 12 and adapted for axial movement, from its retracted position shown, to a position of engagement with an engine-jaw or rotor load element 14 having jaws 16.

A hollow shank portion 17 of the member 10 cooperates with means 18 in accordance with the invention, to be later more fully described, and has an inner spline connection 20 to a hollow screw

shaft 22 having long-lead screw thread connection to a hollow axially stationary rotative nut 24.

Shoulders 26 and 28, on the shaft 22 and the nut 24, respectively, engage each other, after rotation of the nut has caused movement of the shaft to the left, as viewed in the drawing, and the member 10 has been correspondingly moved by the shaft, through the intermediary of a spring 30, into engagement with the engine element 14, to rotate the elements 10 and 14 to start the engine.

A member 32, held by a nut 34 in an opening in a central web portion of the member 10, has a sealing ring 36, compressed by the nut between the members 10 and 32, and is provided with a flange 38 behind a flange 40 of the screw shaft 22. The spring 30 extends between the flange 38 and a backing ring 42 held to the shaft 22, as by a lock ring 44.

20 A barrel 46, rotatively journaled in a housing portion 48, has a closed end wall 50, from which project trunnions 52 carrying planet gears 54 held in place, as by a ring 56, and engaging an orbital gear 58 fixed to the housing portion 48, and a sun gear 60 fixed to a shaft 62 journaled, as by needle bearings 64, in a tubular portion 66 of an annular plate-like member 68 between the shaft 22 and the nut 24 at one side, and the wall 50, at the other side. The tubular portion 66 is closed at its left hand end, as by a disc 70.

25 A torque limiting disc pack 72, having discs splined to the nut 24 and the barrel 46, respectively, is pressed against the member 68 by springs 74, the degree of pressure of which is regulated by a ring nut 76 in the barrel 46.

30 The shaft 62 is connected to other elements completing a gear train for reducing the speed of a driving or motor shaft, to the right of the structure shown, to the desired speed of the barrel 46.

35 A feature of the invention resides in providing the shank 17 with a portion 29 of given diameter, leading in the direction of movement of the member 10, engaging the latter to the engine element 14, and a following shank portion 32 of lesser diameter gradually merged into the leading shank portion 29 by an annular axially extending ramp 34.

40 A fluid seal 86, fixed to a housing portion 88, is maintained around the follower shank portion 32 in radially inwardly pressing sealing engagement therewith during the axial and rotative movements of the member 10.

45 A split ring 90, as of phosphor bronze, forwardly of the seal 86, is maintained in position by rings 92 and 94 fixed to the housing 88 in radial

ly inwardly pressing frictional engagement with the leading shank portion 80 until the jaw member 10 engages the jaws 16 of the engine element 14, whereupon the engine element 14 holds the starter jaw member 10 for the completion of its axial movement, during which the friction ring 90 slides axially downwardly of the ramp 34 to position radially opposite the follower shank portion 82, in non-friction relation thereto during the rotative movement of the member 10. The ramp 34 provides for the return of the friction ring 90 to position on the leading shank portion 80 when the starter jaw member 10 is reversely axially moved to its retracted position, shown.

In Figure 2, in which corresponding parts are designated by corresponding reference numerals, the modification therein shown is similar in construction and operation to the device of Figure 1, with the exceptions that the leading shank portion 80 is longer, the seal 86 operates on the leading portion, instead of on the follower portion 82, and other changes of design are effected in accordance with these differences, each form having advantages over the other.

Although only two embodiments of the invention have been illustrated and described, various changes in the form and relative arrangements of the parts, which will now appear to those skilled in the art, may be made without departing from the scope of the invention. Reference is, therefore, to be had to the appended claims for a definition of the limits of the invention.

What is claimed is:

1. In a direct cranking engine starter comprising a housing, an axially stationary rotatably driven hollow nut, a screw shaft in said nut adapted for axial movement in response to initial rotatably driven movement of said nut and for subsequent rotative movement by the nut, and spring means, the combination of a starter jaw member adapted for movement from retracted position to a position axially outwardly of said housing by said shaft through the intermediary of said spring means during said initial movement for engaging an engine jaw element and for rotative movement by said shaft for rotating the engine jaw element upon said subsequent rotative movement, said jaw member having a shank portion of given diameter leading in the direction of axial movement of said member engaging the latter to the engine element and a following shank portion of lesser diameter gradually merged into said leading shank portion by an annular axially extending ramp, a fluid seal fixed to said housing and maintained around one of said shank portions in radially inwardly pressing sealing engagement therewith during said axial and rotative movements, and a split ring maintained in position by said housing in radially inwardly pressing frictional engagement with said leading shank portion until said jaw member engages the jaws of the engine element, whereupon the engine element holds said starter jaw member for the completion of said axial movement during which said friction ring slides axially downwardly of said ramp to position radially opposite said following shank portion in non-friction relation thereto during said rotative movement, said ramp providing for the return of the friction ring to said leading shank portion when the starter jaw member is reversely axially moved to said retracted position.

2. In a direct cranking engine starter and

the like comprising an axially stationary rotatably driven nut, and a screw shaft adapted for axial movement in response to initial rotative movement of said nut and for subsequent rotative movement by the nut, the combination of means including a starter member adapting the latter for axial movement by said shaft during said initial movement to position engaging an engine element and for rotative movement by said shaft for rotating the engine element upon said subsequent movement, said member having a shank portion of given diameter leading in the direction of said position and a follower shank portion of lesser diameter joined to said leading shank portion by an annular axially extending substantially ramp portion, and a substantially ring-like member maintained in radially inwardly pressing frictional engagement with said leading shank portion until said member engages the engine element for resistance by the latter against rotation, whereupon the engine element holds said member for the completion of said axial movement thereof during which said friction ring rides axially downwardly of said ramp to position radially opposite said following shank portion in non-frictional relation thereto during said rotative movement, said ramp providing for the return of the friction ring to said leading shank portion when said member is reversely axially moved to said retracted position.

3. In a direct cranking engine starter and the like comprising an axially stationary rotatably driven nut, and a screw shaft adapted for axial movement in response to initial rotative movement of said nut and for subsequent rotative movement by the nut, the combination of means including a starter member adapting the latter for axial movement by said shaft during said initial movement to position engaging an engine element and for rotative movement by said shaft for rotating the engine element upon said subsequent movement, said member having a shank portion of given diameter leading in the direction of said position and a follower shank portion of smaller diameter joined to said leading shank portion by an annular axially extending substantially ramp portion, and a substantially ring-like member in radially inwardly pressing frictional engagement with said leading shank portion until said member engages the engine element for resistance by the latter against rotation, whereupon the engine element holds said member for the completion of said axial movement thereof during which said friction ring rides axially downwardly of said ramp to position radially opposite said following shank portion in non-frictional relation thereto during said rotative movement.

4. In a direct cranking engine starter and the like comprising an axially stationary rotatably driven nut, and a screw shaft adapted for axial movement in response to initial rotative movement of said nut and for subsequent rotative movement by the nut, the combination of means including a starter member adapting the latter for axial movement by said shaft during said initial movement to position engaging an engine element and for rotative movement by said shaft for rotating the engine element upon said subsequent movement, said starter member having a shank portion of given diameter leading in the direction of said position and follower shank portion of less diameter joined to the leading shank portion by an annular ramp, fluid seal means cooperating with one of said shank por-

tions, and holding means cooperating with said leading shank portion preventing rotation and providing for said axial movement of said member until the latter engages the engine element for resistance by the latter against rotation and said holding means slides downwardly on said ramp whereupon the engine element holds said member for the completion of said axial movement thereof and the rotation preventing effect of said holding means is released.

5. In a direct cranking engine starter and the like, an axially movable starter clutch member adapted to be held against rotative movement for effecting its axial movement in one direction from initial position for engagement with an engine clutch element for rotating the latter to start the engine, the starter clutch member having a shank portion of given diameter leading in said direction and a follower shank portion of less diameter joined to the leading shank portion by annular means, means cooperating with one of said shank portions for sealing the clutch member during its axial and rotative movements, and means cooperating with the leading shank portion in given position holding the clutch member against rotation until it engages the engine clutch element for resistance by the latter against rotation whereupon the clutch element holds the clutch member for the completion of the axial movement of the latter during which the annular means cooperates with the holding means in movement of the latter from said position on the leading shank portion to a location on said follower shank portion released from holding relation to the clutch member, the holding means being maintained in released location during the clutch member rotative movement and said annular means cooperating with the holding means during the return of the clutch member to the initial

position of the latter to effect movement of the holding means from said released location on the follower shank portion to the said holding position of the latter on the leading shank portion to resume its holding of the starter clutch member.

6. In a direct cranking engine starter and the like, a rotative clutch member axially movable into engagement with a rotative engine element and adapted to rotate the latter to start the engine, means cooperating with one portion of the clutch member for sealing the clutch member during its axial and rotative movements, driving means, transmission means between the driving means and the clutch member including means adapted to effect the axial and rotative clutch member movements, a shaft for said clutch member, said shaft including first and second portions, means cooperating with the first portion of the shaft of the clutch member to hold the clutch member against rotation by the driving means to effect said engagement, and said second portion of the clutch shaft being adapted to release the holding means upon movement of the clutch member into said engagement and thereby permit the driving means to rotate the clutch member, the holding means being arranged to resume holding position on the first portion of the shaft upon return of the clutch member to initial position.
